[57] **CLAIM**

I claim the ornamental design for a tilt-latch, as shown and described.

DESCRIPTION

FIG. 1 is a perspective view of a tilt-latch, embodying the new design;

FIG. 2 is a front elevational view of the tilt-latch;

FIG. 3 is a rear elevational view of the tilt-latch;

FIG. 4 is a top plan view of the tilt-latch;

FIG. 5 is a side elevational view of the tilt-latch; and,

FIG. 6 is an opposite side elevational view of the tilt-latch. The underside of the tilt-latch is plain and ornamented. The broken-line disclosure in the views is for illustrative purposes only and forms no part of the claimed design.
